CLAIM

The ornamental design for a shoe, as shown and described.

DESCRIPTION

The shoe is shown in FIGS. 1-4. The shoe shown is a left shoe. The right shoe is not shown, but is the mirror image of the left shoe.

FIG. 1 is a perspective view of the shoe showing the new design as viewed from the top of the shoe. The shoe upper shown in broken lines is not part of the design sought to be patented and is shown for illustrative purposes only;

FIG. 2 is a top plan view of the shoe;

FIG. 3 is a lateral side elevation of the shoe; and,

FIG. 4 is a medial side elevation of the shoe and sole.
